CLAIM

The ornamental design for a display screen with graphical user interface for glucose management, as shown and described.

DESCRIPTION

The patent file contains at least one drawing executed in color. Copies of this patent with a color drawing will be provided by the Office upon request and payment of the necessary fee.

FIGURE is a front view of a display screen with graphical user interface for glucose management showing our new design.

The outer broken lines illustrate a portion of a display screen and form no part of the claimed design. The text and numerals shown in broken line in the graphical user interface form no part of the claimed design.
